WOOD SCREW GAUGE

George D. Siemantel, Raton, N. Mex.

Application November 1, 1957, Serial No. 693,877

3 Claims. (Cl. 33—178)

This invention relates generally to hand tools, and is more particularly concerned with an improved wood screw gauge facilitating the sorting, sizing and installation of standard wood screws.

The sizing and sorting of wood screws generally requires the use of calipers, rules and other tools and is generally time consuming and unsatisfactory. Additionally, when an individual such as a carpenter or cabinet-maker desires to use wood screws on a given project, unless he has had long years of experience relative to the bit sizes of push drill bits, and thread bits, he must refer to prepared charts which furnish this necessary information. Individuals without the necessary experience, generally do not have access to the graphs referred to, and due to their inexperience generally have difficulty in picking out or interpreting the information provided by the graphs.

A primary object of this invention is to provide a wood screw gauge including means for determining the standard screw number of a given screw, the length of the screw, the body drill bit size, the thread drill bit size and push drill bit size.

Another object of this invention is to provide a center punch gauge to be used when a standard wood screw number is known for determining the body drill bit size, thread drill bit size and push drill bit size to be used when installing a given standard screw, said center punch gauge additionally providing means for supporting a set of center punches to be disposed in the bore drilled for the body of a standard wood screw wherein a suitable mark may be made therewith on an underlying piece of material in order to properly align pieces of stock to be joined by the standard wood screw.

Another object of this invention is conformance with that set forth is to provide in a wood screw gauge means for positioning countersink stops of a drill bit used in installing standard wood screws.

A still further object of invention is to provide in a wood screw gauge of the character set forth means for determining whether a given body drill bit size is oversized, undersized, or the exact dimension of the body of a standard wood screw being used.

More particular objects of the invention will become apparent from the reading of the following description of the preferred embodiment, the appended claims and the accompanying drawings, in which:

Figure 1 is a top plan view of the wood screw gauge of the invention;

Figure 2 is a side elevation of the screw gauge;

Figure 3 is a bottom plan view of the screw gauge;

Figure 4 is a side elevation of the screw gauge opposite the side shown in Figure 2;

Figure 5 is an enlarged section taken on line 5—5 of Figure 1, showing by means of phantom lines the manner in which a screw would be sized by using the gauge;

Figure 6 is a top plan view of the center punch gauge of the invention;

2

Figure 7 is a side elevation of the center punch gauge, the center punch gauge being inverted;

Figure 8 is a side elevation of the center punch gauge looking at the side opposite that shown in Figure 7; and

Figure 9 is a section taken on line 9—9 of Figure 6, showing the manner in which one of a set of center punches would be stored in the gauge, and further showing the manner in which the center punch gauge could be used in aligning two pieces of stock material to be joined by a standard wood screw.

Referring to the drawing in detail, indicated generally at 10 is the novel wood screw gauge comprising in the preferred embodiment an elongated body member 12 formed from any suitable material such as a hard wood, plastic or metal. The body member in the preferred embodiment is disclosed as being substantially rectangular, however, other cross sectional configurations are adaptable, and the body member of the gauge might encompass circular or oval shaped cross section.

Extending through the upper and lower surfaces 14 and 16 of the body member are a plurality of graduated bore portions 18, each of which having a different diameter and conforming to the diameter of the body portion of a standard screw. As indicated, the gauge includes eighteen bore portions comparable to the standard wood screws numbered zero to twenty-four as seen in Figure 2, for example. Indicated at 20 are printed indicia reading "head and body" indicating to a user of the gauge that this side will be facing up when a wood screw is being fitted in one of the bores 18. Each of the bores 18 terminates in a countersunk collar 22 facilitating the adjustment of stops on a countersinking bit, this expedient being utilized when installing flat head screws.

The body member 12 includes a bevelled edge 24 having formed thereon and extending from the end 26 of the body member a linear scale 28 for the purpose of measuring the length of a screw being sized.

The screw gauge may be used with wood screws having flat, oval or round heads.

Considering Figure 2, which is visible as seen when rotating the body member toward an individual from the position shown in Figure 1, formed on the side 30 of the body member are printed indicia 32 designating the "screw number" indicated by numerical indicia 34, each of the numerical indicia being in alignment with one of the bores 18 and designating a standard screw number. Provided on the side 36 of the body member opposite side 30 are printed indicia designated as "body drill bit" as indicated at 38 and comprising fractional numerical 40, each being of a different value in alignment with one of the bores 18 and indicating the body drill bit size for forming a bore to accommodate the body of a given standard wood screw. The edge at the intersection between the side 36 and top 14 of the body member is bevelled as indicated at 42 and includes thereon printed indicia reading "over or under" indicated at 44 and incorporating a plurality of letter indicia as indicated at 46, the letters reading "O" designating that the body drill bit size suggested will be slightly oversized relative to the diameter of a given wood screw. The fact that the body drill bit may be slightly oversized will not be of any consequence when installing wood screws since there is no necessity for controlling the size for the body of a wood screw to small decimal tolerances. The letter "U" indicates that the body drill bit size may be slightly undersized. The letter "B" will indicate that the drill bit suggested will be the exact size for the given wood screw.

Provided on the bottom 16 of the body member and extending the length thereof adjacent side 36 are printed indicia indicated at 48 reading "thread drill bit" and

comprising fractional numerical indicia indicated at 50, each of the numerical indicia being a different value and in alignment with one of the bores 18 and designating the drill bit to be utilized for forming the bore to receive the threaded portion of a given wood screw. Also provided on the bottom 16 of the body member are printed indicia 52 reading "push drill bit" designating the standard push drill bits generally numbered in a set from 1 to 8 as seen in Figure 3, and indicated at 54, said indicia 54 being in alignment with the screw numbers 2 through 16, and indicating to a user of the gauge which push drill bit should be utilized when starting a given screw. Considering "P1," for example, it will be seen that either standard screws 2 or 3 would be installed by utilizing the push drill bit #1. However, it will be seen that push drill bit P7 should generally be used only for installing standard screw 14.

The gauge is used in the following manner:

As seen in Figure 5, it was found that the body of the screw S was received in that aperture 18 in alignment with screw #14. Thus it was readily determined that the screw being sized was a #14 screw, and after measuring the length of the screw using scale 28, other #14 screws having the same length could be readily obtained for a customer, for example, or be sized by a clerk who has a number of assorted unsized screws on hand. After determining that the screw size is a #14, by rotating the gauge and observing side 36, it will readily be ascertained that the body drive bit size should be $\frac{1}{4}$ inch and that this drill bit is slightly oversized. By once more rotating the gauge and viewing the bottom 16 of the gauge it may be readily determined that the thread drill bit size for proper installation of the screw should be $\frac{5}{32}$ of an inch, and the push drill bit size would be a P7.

Thus an individual with relatively little mechanical background and training may readily sort various wood screws, determine the size of various screws in order to obtain the same for customers, and may also readily apprise a customer of the drill bit size data in order to properly install the screw.

Considering Figures 6 through 9, indicated generally at 60 is a center punch gauge comprising a base 62 having suitably secured thereon a body member 64. The body member 64 has formed in the upper surface 66 thereof a plurality of different sized bores 68 conforming the different diametered center punches which normally be stored therein. Adjacent the bores 68 and extending longitudinally of the upper surface of the body member are indicia 70 indicating a standard screw number. Extending longitudinally along one side 72 of the body member 64 are printed indicia reading "body drill bit" as indicated at 74 and comprising fractional numerical indicia 76, each of the numerical indicia 76 being in alignment with one of the bores 68 and designating the proper body drill bit size to be used when a given standard screw number is known. On the other side 78 of the body member 64, see Figure 7, are printed indicia 80 reading "thread drill bit" which comprises longitudinally spaced fractional numerical indicia 82, each of the numerical indicia being in alignment with one of the bores 68 and indicating the proper thread drill bit size to be used with the given known wood screws. Extending longitudinally along the side 78 adjacent the top 66 of the body mem-

ber are printed indicia "P.D.," comprising spaced numerical indicia 84 designating the push drill bit size to be used with a given wood screw.

The center punch gauge is used as follows:

After having ascertained the proper screw number by using the gauge 10, for example, if the screw number is #16, in alignment with this screw number will be the proper center punch C. By referring to side 72 of the gauge, it will readily be determined that the body drill bit size will be $\frac{1}{16}$ inch, and by referring to the opposite side of the gauge it will be readily determined that the thread drill bit size for proper installation of the screw is $\frac{3}{16}$ inches of an inch and the push drill bit size would be a #8.

The determination of the proper center punch is of considerable importance in order to do accurate work, in cabinet-making, for example, the center punch being initially aligned in the bore formed to receive the body of a given wood screw, and being struck to form a proper mark on an underlying piece of stock in order to form the bore by means of the thread drill bit.

Thus there has been disclosed a novel wood screw gauge and center punch gauge which may be readily and economically manufactured, easily used, and practical for individuals skilled or unskilled in the use of wood screws.

The construction shown embodies the invention in a preferred form, but it is intended that the disclosure be illustrative rather than definitive, the invention being defined in the claims.

What is claimed as new is as follows:

1. A wood screw gauge comprising an elongated body substantially rectangular in cross section, said body including a plurality of longitudinally spaced, transverse bore portions each differing in diameter from the others and extending through opposite sides thereof, each of said bore portions conforming to a different body size of a standard wood screw, and plural series of indicia means on each of the sides of said body in alignment with said bore portions, one series of indicia indicating the body drill bit size to be used to form a bore to accommodate a given screw body, a second series of indicia adjacent said bore portions indicating "over size," "under size" or "exact" size of a drill bit as compared with a given screw, a third series of indicia adjacent said bore portions indicating the standard wood screw number of a screw accommodate in a given bore portion, a fourth series of indicia adjacent said bore portions indicating a push drill bit number to be used for a given screw, and a fifth series of indicia in alignment with said bore portions indicating the thread drill bit to be used with a given screw.

2. The structure of claim 1 in which said body is beveled longitudinally at the intersection of two adjacent sides forming a surface upon which one of said series of indicia is disposed.

3. The structure of claim 1 in which each of said body bore portions include an annular countersunk portion for accommodating the head of a wood screw therein.
